UNITED STATES PATENT OFFICE.

JULES MACÉ, OF GRASSE, FRANCE.

PERMUTATION-LOCK.

1,317,304.

Specification of Letters Patent. Patented Sept. 30, 1919.

Application filed April 23, 1918. Serial No. 230,336.

To all whom it may concern:

Be it known that I, JULES MACÉ, a citizen of France, residing at Grasse, Alpes Maritimes, France, have invented certain new and useful Improvements in Permutation-Locks, of which the following is a specification.

My invention relates to improvements in locks, being more particularly an improvement of my patent granted October 2, 1917, Number 1,241,532, and it consists in the constructions, combinations and arrangements herein described and claimed.

An object of my invention is to provide a permutation lock including a casing having a plurality of slidable plates, together with support carrying permutation elements arranged in such manner that they coöperate in obtaining the locking or release of a bolt. Other objects and advantages will appear in the following specification, reference being had to the accompanying drawings, in which:

Figure 1 is a vertical section of the lock, taken substantially on the line 1—1 of Fig. 2.

Fig. 2 is a cross section on the line 2—2 of Fig. 1.

Fig. 3 is a detail view of a section of the permutation elements.

Fig. 4 is a detail perspective view of a portion of the lock.

Fig. 5 is a vertical section taken substantially on the line 5—5 of Fig. 2.

Fig. 6 is a cross section of the lock showing the tumbler disk in the normal position.

Fig. 7 is a detail view of the stop bar and abutment pawls carried thereby.

Fig. 8 is a vertical section on the line 8—8 of Fig. 7.

Fig. 9 is a diagrammatic view showing the normal position of the parts.

Fig. 10 is a similar view showing the position of the parts at the second and third phases.

Fig. 11 is a detail elevation of the dial and pointer.

Fig. 12 is a detail view showing one application of the lock.

Fig. 13 is a similar view hereinafter referred to.

Fig. 14 is a sectional view of a further modification.

Fig. 15 is a diagrammatic view of parts shown in Fig. 14.

It will be observed upon comparison that while the lock structure of this application is alike in some respects to that of my Patent No. 1,241,532, there are however many improved features which have been recently developed and which contribute toward the general efficiency of the lock.

The lock includes essentially the casing 1 which has a horizontal pair of grooves 2 in the top and bottom, and a vertical pair of grooves 3 in the side walls. A bolt plate 5 is slidable in the horizontal pair of grooves 2. The bolt plate has a bolt 6 at one side, which is adapted to engage a keeper on the jamb of a door when the lock is applied to a door.

7 designates a plate that is vertically slidable on the bolt plate 5, as is clearly shown in Fig. 6, by reference to which it will be seen that the plate 7 includes a sleeve 9 that extends through the front wall of the lock casing 1. A shaft 8 is journaled in the sleeve 9 and extends forwardly through the plate 7, and the inner end 10 of the said shaft 8 is threaded and carries a disk 10 that constitutes a support for the adjustable baffles presently explained.

The disk 11 has an internally threaded hub 12 that engages the threaded end of the shaft 8, as shown, and the said disk includes a flange and a back or rear wall 14, the flange forming the annular wall of a hollow space 13 in which the adjustable baffles mentioned are located, as is best shown in Figs. 5 and 6.

The concentric element supporting rings 15 and 16 are supported in the proper relative positions by outer and inner sets of rollers 17 and 18 respectively. The outer set of rollers 17 engages an external rib 19 on the outer ring 15, the inner set of rollers 18 engages an internal annular spline 20 on the inner ring 16. Each roller of the two sets is journaled upon a pintle 21 which is firmly seated in the wall 14. The front ends of the pintles 21 are supported in bearings 22. The bearings 22 may consist of separate pieces secured to the front surfaces of the disk 11 and hub 12 respectively, as shown in the drawings, or they may consist of integral parts of the disk 11.

The outer ring 15 carries three sets of baffles 23, 24 and 25 while the inner ring 16 carries three coating permutation elements 26, 27 and 28. These elements may vary in number for each ring and they may be changed in length and location. It will be readily understood from Fig. 5, that the permutation elements, projecting into the channel between the two rings as they do, 10 form a tortuous passage. A latch 29 is located in this tortuous passage and the security of the lock lies in the difficulty of manipulating the support 11 without the latch 29 engaging the baffles.

15 The adjustable baffles on the outer and inner rings respectively, are fitted into grooves 30 and 31. These grooves are dovetail in shape, to receive and hold the dovetail shaped base portions 32 of the baffles. 20 The rear walls of the grooves 30 and 31, are formed by key rings 33 and 34 which are screwed in place. It will be understood that the individual sections of the adjustable baffles are put in place and adjusted to the 25 substantially correct positions, when the key rings are screwed in place to hold the sections. The key rings will eventually bind the sections of said elements in position. By loosing either ring, the baffles may 30 be moved to new positions to change the combination of the lock.

The supporting rings 15 and 16 have predetermined relative positions with respect to each other and are adapted to rotate with 35 the disk 11. For this purpose, the tension between the various rollers and rings, is sufficiently great to carry the rings with the disk when it is turned. It is only when the 40 lock is poorly manipulated, as by one who does not know the combination, that tension between the rollers and the rings is disturbed, and the rings forced out of the proper positions.

45 The disk 11, together with the rings, is adapted to be turned in a clockwise direction. Counterclockwise movement is ordinarily prevented by the engagement of pins 35 and 36 on the outer and inner rings, with abutment pawls 37 and 38 pivoted on a stop 50 bar 39 carried by a brake 40. The stop pawls are arranged substantially as shown in Fig. 7. They rest against pins 41 and 42 at the backs of the pawls.

55 The stop pins may readily pass under the respective pawls when the disk 11 rotates in the clockwise direction, but the pawls tend to stop the rotation of the disk in the counterclockwise direction. The rings, of course, must stop since the pins are fixed 60 thereon. But the disk 11 may be forced around against the existing tension between the rings and the disk thus disaligning said parts as previously explained.

65 The brake 40 is pressed against the bottom of the disk 11 by a leaf spring 43 sup-

ported on a bar 44 which projects inwardly from the bolt plate 5, see Fig. 6. The brake 40 has upward extensions at the front and back to hold it in position on the disk. The spring is pivoted to the brake and the bar 70 44, so that the brake may follow the longitudinal and lateral movements of the disk 11.

The disk 11, together with the bolt plate 5, is adapted to be moved laterally to 75 retract the bolt 6, after the combination has been properly manipulated. This lateral movement is prevented when the parts are in the first or initial position, by a stop plate 45 arranged to engage one side of the 80 disk at this time. The stop plate 45 projects from a bracket 46 having beveled edges fitted into a recess 47 with similarly beveled edges in an arm 48. The arm 48 is carried by a bit plate 49 which is vertically movable in the grooves 3 in the casing. A spring 50 presses the end of the bracket 46 against the plate 49 at the base of the recess 47 in which the stop plate 45 is mounted.

A pair of pins 51 and 52 are fixed upon the shaft 8, at either side of the disk 11. The pin 51 engages a stud 53 on the hub 12, when the disk is in the initial position shown in Fig. 6. A stud 54 on the front of the disk 11 is adapted to engage the pin 52 when the disk assumes the second position. The stud 53 is disposed in a recess 55 at the back of the disk 11. The recess 55 also accommodates the pin 51 when the disk is in 100 the first position, so that the parts may be moved closely together.

105 A gear 56 on the rear end of the shaft 8, is adapted to mesh with a pinion 57 when the parts are in the bolt retracted position. The pinion 57 is mounted on the end of a gas cock 58 which may be located in the casing of the lock, as shown, or in some other location. The illustration in Fig. 2, is virtually that of two embodiments of the 110 invention. The gas cock 58 may, of course, be incorporated in the lock casing and capable of being operated together with the bolt of the lock. But ordinarily the mechanism of the lock will be used in one connection only; namely, either as a lock mechanism *per se*, or a lock for a gas cock.

115 Bits 59 and 60 on the bit plate 49, coat with the rings 15 and 16 carried by the disk 11, after the disk 11 reaches the second position, as shown in Fig. 2. The bit 59 is relatively long, while the bit 60 is relatively short. The bits are spaced apart to leave a passage 61 in which the outer ring 120 moves.

125 A tightly wound coil spring 62 supports the latch 29. The spring 62 is mounted on a stud 63 which projects inwardly from the bolt plate 5. The purpose of the spring support 62 is to provide a slightly yielding 130

mounting for the latch so that a breakage may not result in the event of the latch becoming accidentally caught.

The shaft supporting plate 7 carries the bit plate 49 with it in the vertical movements of the plate 7. This is accomplished through a pair of pins 63 on the plate 7, which project through an opening 64 in the bolt plate 5, and engage horizontal grooves 65^a in the bit plate 49. The opening 64 has beveled ways in which the beveled edges 64^a of the shaft supporting plate 7 fit.

The positions of the disk 11 during rotations, are traced on a dial 65 on the front 15 of the casing 1, by a pointer 66 on the shaft 8. The dial 65 is graduated in degrees which are suitably numbered so that they may be more readily followed. The distances in 20 degrees that the pointer 66 is moved over the dial 65, correspond to the distances between the abutment shoulders of the various permutation elements. The pointer and 25 graduations thus act as guides whereby the operator may know when to raise and lower the disk 11 to avoid contact between said shoulders and the latch 29.

A knurled knob 67 is fixed on the outer 30 end of the shaft 8 so that the shaft may be easily turned. A key 68 on the shaft supporting plate 7, engages an annular groove 69 in the shaft 8. The key 68 prevents the longitudinal movement of the shaft 8, and yet permits it to turn freely in manipulating the combination of the lock.

35 Bit passages 70 and 71 are formed in the outer edges of the rings 15 and 16 respectively. These passages are normally in alinement, as shown in Fig. 5. They are to be moved into coincidence with the bits 59 40 and 60, when the disk 11 may be moved over and the bolt 6 retracted. Guards 72 extend radially inward from the passage 71 and they bridge the space 61 between the bits when moving the disk 11 laterally, so 45 that the inner ring 16 may not be turned into said space through an inadvertent turn of the knob 67.

Figs. 14 and 15 illustrate modification of 50 the lock, wherein a click for following the positions of the disk is embodied. In this form, the shaft 8 is fixed at one end in a plate 87 in turn vertically movable in a supporting-plate 88. A screw stud 68^a takes the place of the lug 68 in Fig. 6, and engages 55 the groove 69, as shown. The plate 87 is held in its elevated positions by the engagement of a serrated keeper 89 on a pendent spring 90, with a dog 91 mounted on the plate 88.

60 The pulsator consists of a gear and ratchet arrangement 92 associated with an actuating shaft 93, as in my patent dated October 2, 1917, No. 1,241,532. The shaft 93 has a pinion driving a gear 94. The gear 94 is

fastened on a screw sleeve 95 which supports the hub of the brake disk 96.

Disks 111 and 111^a are secured at the sides of the brake disk.

Overhanging flanges form parts of these disks, and one of these flanges house the 70 baffles, as shown at the right in Fig. 12. The baffles of the said disk 111 are located on the inner surface and latches 29 and 29^a coöperate with the respective sets of elements.

Mounted upon a bar 97 at one side of the 75 disks 111, is a pair of latch rods 98 which carry the latches 29 and 29^a. The ends of the bar 97 bear against springs 62 and 62^a which provide a mounting with a degree of resiliency. The bar 97 is mounted on the 80 supporting plate 88, substantially as shown. It will be observed that some of the parts shown in Fig. 14 are omitted from Fig. 15. This is for the purpose of defining the relative positions of the latch rods with respect 85 to the permutation elements. The edge of the brake disk is concave so as to more readily hold the brake 40 on the spring 43. The spring 43 is supported by a bar 44 which projects from the plate 88. 90

This form of the lock is operated similarly to the other forms, the shaft 93 forming the means by which the various manipulations are made. It should be observed that the plate 87 includes a square boss 99 95 which projects through an L shaped slot 100 diagrammatically shown in Fig. 15. The horizontal and vertical portions of this slot accommodate the necessary horizontal and vertical movements of the plate 87 and its 100 associated parts.

The operation of the lock is as follows: The first or normal position of the disk 11, when the bolt 6 is projected, is that shown in Fig. 6. Here the disk 11 is shown as far back as it will go and from this position, the disk moves through the successive stages which constitute the required manipulation for unlocking the lock. The latch 29 is out of alinement with the permutation 110 elements 23 *et seq* on the inside of the rings 15 and 16. The disk 11 engages the arcuate abutment 45, thus preventing the lateral movement of the parts and the retraction of the bolt 6. The pointer 66 points to "0" 115 on the dial 65.

The second stage is reached when the disk 11 assumes the position indicated in Fig. 2. Here it will be seen, the disk has advanced from the rear wall of the casing 1 120 and has cleared the arcuate abutment 45. The disk 11 is advanced to the second stage by turning the knob 67 through a predetermined number of degrees which is read off the dial 65. The brake 40 prevents the rotation of the disk 11 while it advances. During this initial rotation of the shaft 8 through the knob 67, the screw threads 125

caused the disk 11 to advance, the pin 51 leaving the stud 53. The stud 54 on the front of the disk engages the pin 52 on the shaft 8 at the end of the second stage. The 5 latch 29 will also be disposed between the rows of permutation elements at this time as shown in Fig. 2.

Subsequent rotation of the shaft 8 turns the disk 11 through the engagement of the 10 pin 52 and stud 54. The third and ensuing stages now follow in succession. The end of each stage is reached when the latch 29 occupies a position adjacent to a shoulder of one of the permutation elements. It is 15 then that the disk is either raised or lowered to avoid contact with the shoulder when the rotation may be continued until the next stage is reached. Although the permutation elements are shown smooth in the principal 20 views of the drawings, they are actually constructed as shown in Fig. 3. Here certain of the sections of said elements are provided with teeth very much on the order of saw teeth.

25 The final stage is reached when the bit slots 70 and 71 are in registration with the bits 59 and 60. The bolt plate 5 may then be moved laterally to retract the bolt 6. The gear 56 will also engage the pinion 57 when 30 the cock 58 may be turned. In conclusion, it should be stated that there is another possible and entirely practicable method for remembering the various combinations to which the lock may be set. For instance, the 35 permutation elements may be arranged according to the words of a familiar quotation, each word representing an easily remembered number of degrees of rotation according to the length of the word. The quotation may then be written down, if desired, 40 without attracting the undue attention the notation of an equal number of numerals might excite.

While the construction and arrangement 45 of the device is that of a generally preferred form, obviously modifications and changes may be made without departing from the spirit of the invention or the scope of the claims.

50 What I claim is:

1. In a lock of the character described, a casing, a rotatable shaft, a disk, screw feed connections between the shaft and the disk, whereby rotation of the shaft feeds the disk 55 along the shaft, the said shaft and disk having lateral movement relatively to the casing, means for holding the shaft and disk from lateral movement under one adjustment of the disk on the shaft, rings carried 60 by the disk and rotatable with the disk, at times, means for holding the rings from rotation, at times, baffles on the opposing surfaces of the rings and a latch adapted to coact with the said baffles during a predetermined stage in the operation of the lock.

2. In a lock of the character described, a casing, a laterally movable disk disposed within the casing, a pair of rings carried by the disk having portions extending beyond the front surface of the disk, a plurality of 70 baffles disposed on the inside surface of the rings and in the extending portions thereof, a latch adapted to be located between the rings to coact with the said baffles, means for advancing the disk until the extending 75 portions of the rings are circumscribed on the latch and other means for holding the disk with the rings from lateral movement, when adjusted to the initial or normal position.

3. In a lock, a casing, a disk disposed in 80 the casing, means for advancing the disk to a forward position and subsequently turning the disk, baffles supported by the disk in a plane in front of the disk, a latch adapted for co-operation with said baffles, when the 85 disk is in the advanced position, and a resilient mounting for the latch, the said resilient mounting comprising a tightly wound coil spring attached at one end to a relatively fixedly held portion of the lock and whose 90 free end carried the latch.

4. In a lock, the combination of a bit plate, an arm carried by the bit plate, having a recess and a bent end, a disk located behind the bit plate, a stop plate mounted in said 95 recess and engaging the disk when in one position, and a spring located between the stop plate and the said bent end.

5. In a lock, the combination of a bit plate having an arm, a plate slidable on the arm 100 and limited in movement in one direction, means urging the plate to said limit of movement, and a disk adapted to be engaged by said plate when the disk is in one position.

6. In a lock, the combination of a bit plate, 105 an arm on the bit plate with a recess and a bent end, a stop plate having a bracket slidably mounted in the recess, said bracket engaging the bit plate in its forward movement, means disposed between the stop plate 110 and said bent end urging said plate to the bit plate engaging position, and a disk adapted to be engaged by the stop plate.

7. In a lock, the combination of a bit plate, bits, a stop plate, a yieldable mounting on the bit plate for said stop plate, a 115 disk, and rings on the disk adapted to coact with said bits.

8. In a lock, the combination of a bit plate, bits, a stop plate, a mounting on the 120 bit plate for said abutment, a disk engaging said stop plate in an initial position, rings carried by the disk, adapted to coact with the bits when advanced to a second position, and means for advancing the disk to the 125 second position.

9. In a lock, a disk, a plurality of rings mounted in the disk, each ring having an annular rib, and rollers carried by the disk, 130 engaging said rib to support the rings.

10. In a lock, a disk having a hollow space, a pair of rings concentrically arranged, an annular rib on the outer surface of the outer ring, an annular rib on the inner surface of the inner ring, and rollers journaled on the disk in engagement with said rib to frictionally hold said rings.

11. In combination with a supporting plate, a tumbler disk having means providing a support therefor from said plate, per-

mutation elements carried by said disks, co-acting means in operative relationship to said elements, supporting means for said coacting means extending from said plate, and resilient elements embodied in said supporting means. 15
